UNITED STATES PATENT OFFICE.

HARRY ALTON DAVOL, OF METHUEN, MASSACHUSETTS, ASSIGNOR TO U. S. BOBBIN & SHUTTLE CO., OF PROVIDENCE, RHODE ISLAND, A CORPORATION OF RHODE ISLAND.

TENSION DEVICE FOR SHUTTLES.

Application filed March 16, 1926. Serial No. 95,128.

This invention relates to threader blocks such as are used in shuttles, particularly those of the self-threading type.

It is particularly useful in connection with yarns of artificial silk, rayon, and other material which requires considerable carefully adjusted friction to prevent it from throwing or getting out of position.

It comprises an adjustable friction plate 10 positioned between a friction member and a holding pin, having a hole between them for the passage of the whole or part of an adjusting guide screw, and a tension spring which bears on or is a part of the friction 15 plate and whose pressure can be altered by said screw.

All these parts are so made and positioned that they can readily be removed and replaced by others.

20 In the drawings, Fig. 1 is a plan view of one end of a shuttle provided with my device.

Fig. 2 is a bottom plan view of the threader block removed from the shuttle.

25 Fig. 3 is a side elevation of the shuttle block from the side opposite the guide eye.

Fig. 4 shows a modified type of spring.

Fig. 5 is a side elevation of a shuttle 30 block, from the side where the shuttle eye is located.

Fig. 6 is a back perspective and Fig. 7 is a front elevation of my shuttle block removed.

Fig. 8 is a plan view of one end of a hand 35 threading shuttle provided with my device.

Fig. 9 is an elevation of the reversible shuttle block shown in Fig. 8 from the side opposite the shuttle eye as it appears removed from the shuttle.

40 Fig. 10 is a back view or view from the right of Fig. 9 and Fig. 11 is a front view or view from the left of Fig. 9.

Fig. 12 is a plan of another modified type of friction plate.

45 Referring to the accompanying drawings, W indicates the body of the shuttle having a bobbin recess 1 in which is positioned the bobbin B of the usual kind, from which the thread Y extends through the threader block R in substantially the usual manner. There is the usual threading chamber 4 in the wood, and the corresponding threading chamber 5 in the threading block.

50 The top 20 of this block R is substantially flat and slopes down at 21 to a front hook

23, and at the back to a back hook 22, in a well known manner.

The horn 32 is of the usual construction, but as shown in Fig. 3, the thread pin 30, preferably slopes down and back so as to help keep the yarn down on the hard steel pin, or other bottom friction F.

F may be a pin of hard steel or a cylindrical piece of glass, felt, or in fact any other suitable material extending transversely 65 across the bottom, towards the front of the threading chamber.

The top friction is a plate H, preferably of sheet metal, which is flat at the bottom and extends up in what might be called a 70 tail 40, the end of which rests against or around a holding pin 41 which extends across the upper back part of the threading chamber. It is held up at the back and prevented from moving sideways by this pin 75 41 but it can readily be removed when screw A is removed.

At its front end 42, it rests on the bottom friction F.

There is also through it, a tension screw 80 hole 45 which registers with a hole 46 in the bottom of the block, and with a recess 25 at the top of the block whereby tension screw A, having the head 50 and shank 51, threaded at 52, can engage both of these holes from the recess 25. This tension screw A is encircled by tension spring B between its head and the part 42 of friction plate H. 85

Friction plate H also has an upwardly extending guide tongue 43 which extends up and inward between the front hook 23 and back hook 22, and serves to guide the thread Y down underneath part 42 and over the bottom friction F.

The tension can be adjusted by turning 90 screw A, and by removing screw A, the friction plate H can be taken out and replaced, and the spring B can also easily be replaced.

At the same time, the bottom friction F can be removed by knocking it out from the 100 side.

I preferably utilize the usual stud 26 which extends down from the shuttle block R to receive the threaded end of screw A as this gives it a long bearing.

105 As shown in Fig. 4, the friction plate such as L may itself be a spring, thus eliminating spring B.

The ends of L rest respectively on friction means F and holding pin 41 while the ad- 110

justing screw M is threaded at 131 into the body 132 of the threading block and has a head 130 which rests or bears against washer 135 on top of L.

5 The width of the tail such as 40 should preferably be slightly less than the exposed part of pin 41 so that there will be little lateral motion. This, together with the screw B which passes through guide screw hole 45, 10 holds plate H in position from lateral movement while the vertical movement is resisted by spring B.

By removing the screw such as A or M, spring B if used, and plate H or L, can readily 15 be slipped out.

In Figs. 8, 9, 10 and 11, I show a hand threading shuttle T having the usual threading slot 150 and thread guide pin 151 with a double ended block P in place.

20 This has at the front and back, the back guides 61 and 62, in each of which may be inserted a holding pin such as 63 from a hole such as 64 at each end of the top of the threading chamber 60, while at the front 25 and back at the bottom, are the holes 66 and 67, through which may be passed either a retaining screw to hold the block in place, of the usual type, or a friction member such as F.

30 The friction plate R may be the same as H but it is obvious that by turning it end for end as shown by the dotted lines in Fig. 9, this block can be used in a shuttle with either a right hand eye or a left hand eye. The 35 only difference is that the friction plate is reversed and the bottom friction member changes places with the holding screw in the holes 66 and 67.

As shown in Fig. 12, I may use a friction 40 plate 70 having a tail 71, a screw guide hole 74, and a wide guide tongue 72 which is bent in at 73 so that it will partly extend over the head of a screw such as A shown in the dotted line.

45 I claim:

1. The combination in a threading block for shuttles having a threading chamber, a back guide which extends downward into said chamber, and a screw recess; of a bottom friction member positioned near the front bottom part of said threading chamber; a holding pin positioned near the back top part of said threading chamber; a friction plate positioned on and between said 50 friction member and said holding pin, said

friction plate having a guide wing which cooperates with said back guide and a medially located tension screw hole; a screw which extends vertically through said screw hole in line with the screw recess, and enters the 60 bottom of the threading chamber; and a tension spring which surrounds said screw between its head and the friction plate.

2. The combination in a threading block for shuttles having a threading chamber, a 65 back guide which extends downward into said chamber, and a screw recess; of a bottom friction member positioned near the front bottom part of said threading chamber; a holding pin positioned near the back 70 top part of said threading chamber; an elastic friction plate positioned on and between said friction member and said holding pin, said friction plate having a guide wing which cooperates with said back guide and a medially located tension screw hole; and a 75 screw having a head which bears on the friction plate and a shank which extends vertically through said screw hole in line with the screw recess and enters the bottom of the 80 threading chamber.

3. The combination in a threading block for shuttles having a threading chamber; of a bottom friction member positioned near the front part of said threading chamber; a 85 holding pin positioned near the back part of said threading chamber; a friction plate positioned on and between said friction member and holding pin and having a medially located tension screw hole; a screw which 90 extends vertically through said screw hole and enters the bottom of the threading chamber; and a tension spring between the screw head and the friction plate.

4. The combination in a threading block 95 for shuttles having a threading chamber; of a bottom friction member positioned near the front part of said threading chamber; a horizontal holding pin positioned near the top back part of said threading chamber; a friction plate positioned on and between said 100 friction member and holding pin and having a medially located tension screw hole; a screw having a head which extends vertically through said screw hole and enters the bottom of the threading chamber; and a tension spring between the screw head and the friction plate.

HARRY ALTON DAVOL.
